UNITED STATES PATENT OFFICE

2,550,546

MAGNETIC SNAP ACTION SWITCH

Theodore N. Flight, Slough, William H. Wilson, Camberley, and Arthur John Chinn, Slough, England, assignors to The Rheostatic Company Limited, Slough, England, a British company

Application July 17, 1948, Serial No. 39,276
In Great Britain July 26, 1947

4 Claims. (Cl. 200—67)

1

This invention relates to magnetic snap action switches, for use on alternating current circuits, of the micro-gap type in which contacts of relatively large mass and of a metal having good heat conductivity are associated with an armature, a spring lever and a permanent magnet, the moving contact being arranged to have a movement of separation from the fixed contact limited to an amount sufficient only to prevent the re-striking of an arc at the voltage of the circuit broken and at such a speed as to reach this distance within the time of half a cycle.

In the usual type of such switches with a single armature the load on the end of the spring switch-lever is equal to the total magnetic force or pull on the armature. This load is usually far in excess of that necessary to assure adequate contact pressure and due to the physical characteristics of the materials used in, and the smallness of the parts of, such switches, the aforementioned load on the switch-lever is inconvenient to provide for. This invention contemplates a switch in which the load on the switch lever is reduced to a value more nearly equal to the relatively small load required to assure adequate contact pressure.

In the preferred form of the invention a resilient switch lever carries a double armature structure so disposed in relation to the magnet that the load borne by the resilient lever is only the difference in the magnetic pull on the two armatures. It is then provided that the magnetic pull on one armature is in all positions of the switch greater than on the second armature, resulting from an adjustable magnetic bias which can be arranged to act in a specific direction relative to the switch contacts, i. e. bias either to the open or to the closed switch position.

Thus, when the armature structure comprises two similar armature elements mechanically connected together, and mounted one on each side of a magnet, the magnet will exert a force on the armature structure in one direction and also a force in the opposite direction. According to the invention, the armature structure is so positioned relative to the magnet that the resultant of the forces exerts a bias in the same direction on the switch lever during movement of the movable switch contact carried thereby both to its open and closed positions and while it is in said positions. That is, one armature is always maintained nearer to the magnet than the other armature in all positions of the switch lever arm, so that the force on the former armature will always be larger than that on the latter armature.

2

In an alternative form of the invention, one of the armatures has a magnetic permeability higher than the other. Since the force on each armature is proportional to the permeability of the material from which the armature is fashioned, a greater force will be exerted on the higher-permeability armature. The permeabilities can be so arranged that a greater force is exerted on the higher permeability armature in all positions of the lever arm.

To provide for the proper magnitude of pressure between the contacts at the moment the contacts make, a relatively high force change is necessary. This force change is caused by movement of the armatures and in a switch constructed in accordance with this invention, is equal to the sum of the force changes on the two armatures. Thus, if the armature approaching the magnet experiences an increase in force of 30 dynes, and the armature receding from the magnet experiences a reduction in force of 30 dynes, the pressure between the contacts at the moment of make will be proportional to the total force change, 60 dynes.

25 In switches according to the preferred form of this invention the lever carrying one contact of the switch and the twin armature unit is a resilient member rigidly supported from the switch base and receiving movement from an actuator such as a thermal member of a thermostat, the moving portion of a pressure sensitive element or any other actuating device. The gradual movement of the actuator is stored in the resilient lever as a force tending to separate the switch contacts and when this force exceeds the set pressure difference existing between the magnet and the two armatures the switch contacts separate with a snap action.

The invention is illustrated in the accompanying drawings in which Figure 1 represents a perspective view of one embodiment of the improved switch of the invention, and Figure 2 is a view of the improved switch using a high coercivity magnet of short rectangular form.

45 In the construction shown in Figure 1 a twin armature unit consisting of two armatures 11, 12 rigidly attached to each other and to the end of the resilient lever 13 embraces the poles of the magnet 14. With actuator 16 withdrawn from contact with the resilient tongue 13 the pressure between contacts 17, 18 is proportional to the adjusted difference in the pull of the magnet on armatures 11, 12. The pressure and movement of the actuator 16 against the resilient tongue 13 generates a force in tongue 13 in opposition to the

resultant magnetic pull between the twin armature unit 11, 12 and the magnet, and when the movement of actuator 16 has generated sufficient force to overcome this pull the switch opens to the aforementioned limited amount with a snap action. It will be seen that in a switch according to this invention the total load to be borne by the resilient switch lever 13 at the moment of switch opening is merely the adjusted out-of-balance attraction existing between the two armatures 11 and 12 and the magnet 14.

In Figure 2 all of the parts are similar to those in Fig. 1 and have similar reference numerals with the exception of the magnet 20 which is in this figure shown as a short rectangular magnet which is rigidly attached to the base by clamping means (not shown) and is completely embraced on two sides by the twin armature unit. This construction so increases the magnetic efficiency of the armature magnet assembly that it is possible to obtain the required pressure between such contacts with magnets of high coercive material weighing only a fraction of what has been previously found necessary.

In co-pending application Serial No. 718,636, filed December 27, 1946, now Patent No. 2,518,966, August 15, 1950, there is disclosed and claimed a magnetic snap action switch which is constructed in accordance with these principles but which employs a non-resilient armature-carrying lever actuated by a resilient member. In a second co-pending application Serial No. 64,326, filed December 9, 1948, now Patent No. 2,519,558, August 22, 1950, there is disclosed and claimed a thermostatically controlled device employing a switch constructed in accordance with the disclosure herein.

We claim:

1. A magnetic snap action switch comprising a magnet, a movable resilient lever arm, a pair of armature members carried by said resilient lever arm for movement therewith and disposed on opposite sides of said magnet, a pair of switch contacts, one of which switch contacts is actuated by said resilient lever arm, the second contact being fixed in position relative to said first contact and adapted to cooperate therewith, and means for limiting the movement of the resilient lever arm in switch-opening direction, the relative magnetic properties of the armature members and their relative distances from the magnet being such that the resilient lever arm is biased in one direction in all of its positions.

2. A magnetic snap action switch as defined in claim 1 in which one of said armature members is positioned nearer to said magnet in all positions of the resilient lever arm than the other of said armature members and the relative magnetic properties of said armature members are such that the resilient lever arm is always biased in a direction tending to move the armature member nearer the magnet toward the magnet.

3. A magnetic snap action switch as defined in claim 1 in which one of said armature members has a greater permeability than the other, and the relative distances of the armature members from the magnet are such that the resilient lever arm is always biased in a direction tending to move the higher permeability armature member toward the magnet.

4. A magnetic snap action switch comprising a movable resilient lever arm pivoted at one end 20 and having a contact fixed thereto adjacent its other end, a pair of armature members mounted on said resilient lever arm and extending substantially parallel thereto, a magnet fixedly mounted relative to said resilient lever arm and positioned between said armature members, a second contact fixed in position relative to said resilient lever arm such that one of said armature members is nearer to the magnet than the other in switch-closed position, and means for so 30 limiting the movement of the resilient lever arm in switch-opening direction that the one of said armature members which is the nearer to the magnet in switch-closed position remains the nearer to the magnet in all other positions of the resilient lever arm, whereby the resilient lever arm is biased in the same direction in all of its positions.
